United States Patent Office.

ANDREW J. ROCK, OF UNION VILLAGE, VIRGINIA.

Letters Patent No. 77,764, dated May 12, 1868.

IMPROVED LAST AND SHOE-HOLDER.

The Schedule referred to in these Letters Patent and making part of the same.

TO ALL WHOM IT MAY CONCERN:

Be it known that I, ANDREW J. ROCK, of Union Village, Northumberland county, State of Virginia, have invented an Adjustable Last and Shoe-Holder; and I do hereby declare the following to be an exact description thereof, reference being had to the accompanying drawings, and to the letters of reference marked thereon, making a part of this specification.

The nature of my invention consists in two upright posts, moving or adjustable in a dove-tail groove in a base-block. The posts are graduated by a regulating-screw. Between the posts is an upright screw, upon which a clamp-block rests crosswise. On this block or base a screw-clamp or jaws operate in a dove-tail groove. The jaws hold the last firmly, whilst the last rests on each upright post, covered with leather or an elastic cushion.

The object of my invention is to make a boot or shoe-support and holder whilst being sewed or pegged, so as to avoid the use of the last on the knees of the workman, and to enable him to work with his shoulders and chest erect, and prevent his stooping over his work, and injuring his health, as usually the result.

A represents the base or block upon which the holder is adjusted, the whole to be made of wood or metal. On the top of this block is a dove-tail groove, B, in which two upright posts, C, fit and are adjusted to either side, and are regulated and held firmly by the screw D. Between the posts C is an upright screw, E, that works in the base, A, and also in the upper block, G, and supports the upper block G, and also raises and lowers the block G when required. In this block G is also a dove-tail groove, H, in which the jaws J J operate, and are also regulated and adjusted backward and forward, and are held firmly by the screw K, so as to hold the last, L, at top and enable the last to be adjusted to any position required whilst the workman is sewing or pegging the shoe, fitted to the last. In place of the last, at any time the workman requires to prepare his leather by stretching or hammering it, he removes the last, L, and inserts a stone or iron plate (commonly called the lap-stone) in place of the last, and hammers and stretches the leather on this machine instead of upon the knee, as usual, saving an uncomfortable operation to the workman.

What I claim as my invention, and desire to secure by Letters Patent, is—

The arrangement and combination of the adjustable posts C, screws D, E, and K, blocks A and G, when adjusted and operated with the adjustable jaws J J, as herein described and for the purposes set forth.
